UNITED STATES PATENT OFFICE

JOHN M. WILKINSON, OF WELDA, KANSAS

SCYTHE BLADE SHANK HOLDING CLAMP

Application filed November 26, 1929. Serial No. 409,810.

This invention relates to scythe blade holding clamps, and has for its object to provide a construction whereby a scythe blade shall be securely fastened in place and the shank of the blade and the handle shall be both strengthened at the point where the greatest imposition of strain occurs in the operation of the scythe. A further object is to produce a construction by which a scythe blade can be secured to or removed from a handle quickly and easily and which is of simple, strong, durable and inexpensive construction.

With the above named objects in view the invention consists in certain novel and useful features of construction and combinations of parts as hereinafter described and claimed; and in order that it may be fully understood reference is to be had to the accompanying drawings in which:

Figure 1 is a fragmentary perspective view of a scythe embodying the invention.

Figure 2 is an enlarged section taken in the longitudinal plane of the center of the handle, but showing the clamping sleeve and clamping blade only in section.

Figure 3 is a detail perspective view of the skeleton sleeve of the invention.

Referring now to the drawings in which like reference characters identify corresponding parts, 1 indicates the handle of the scythe, the same being of any suitable type and configuration throughout the greater part of its length (not shown) but of substantially semi-circular form in cross section at the end adjacent the blade of the scythe, hereinafter identified.

Fitting snugly on the semi-circular portion or end of the handle, is a skeleton sleeve comprising essentially a flat plate 2 and a pair of depending U-shaped portions or yokes 3 and 4, the plate fitting flatly against the flat side of the handle and the yokes engaging the rounded surface of the latter, and said yokes are connected by a longitudinally extending tie piece 5 disposed opposite and parallel with plate 2.

The plate is provided at one end with a pair of upstanding spaced lugs 6 and near its opposite end with a pair of upstanding spaced lugs 7, and beyond one of said lugs

one side of yoke 3 is turned inward at 8 to form a shoulder in line with the inner face of the adjacent lugs 7, the lugs 7 being provided with bolt holes 9 through which protrude clamping bolts 10 extending up through the plate 2.

The blade 11 of the scythe abuts endwise at its handle end against the shoulder formed by the inturned portion 8 of yoke 3, and the shank 12 of the blade fits flatly on plate 2 and snugly between the lugs 7 and the lugs 6, which lugs in conjunction with the inturned portion 8 serve to hold the shank against lateral movement by opposing the strain incidental to a cutting operation.

To secure the heel end of the blade and the shank 12 firmly upon the plate 2, a pair of clamping nuts 13 engage the upper ends of the bolts 10 and a clamping plate 14 which bridges and rests upon the shank 12, it being noted in this connection that said shank projects to a higher plane than lug 7, so that the full clamping action of the nuts 13 upon the plate 14 shall be attained and transmitted from the latter to the shank.

To cooperate with the clamping plate 14 in holding the shank flatly upon plate 2, a bolt 15 extends up through plate 2 near the opposite end of the latter from the blade, said bolt also extending through the shank, and a clamping nut 16 engages said bolt and the shank. To still further guard against lateral edgewise or twisting movement of the shank under the imposition of the strain imposed thereon in the cutting operation, the shank is provided with a plurality of depending lugs 17 engaging openings 18 in the plate 2, and to guard against slippage or creepage of the skeleton sleeve upon the handle, a bolt 19 extends down through an opening 20 in plate 2 and also through the handle and the underlying tie-piece 5 of the clamping sleeve and a clamping nut 21 engages the threaded end of the bolt and said part 5.

It will be apparent that by uniting the blade and the shank thereof to the handle by means of a clamping sleeve of the character described, a most stable, strong and rigid connection is provided, and that by simply removing clamp plate 14 and nut 16, it is

possible to lift the blade from position without disturbing the clamping sleeve at all, and that to replace the blade, it is simply disposed with its shank between the pairs of lugs 6 and 7 and upon the bolt 15, the clamping plate and nuts 13 and 16 being then restored to operative position.

From the above description, it will be apparent that I have produced a scythe blade holding clamp embodying the features of advantage set forth as desirable in the statement of the objects of the invention and which may be modified in minor particulars without departing from the spirit and scope 15 of the appended claims.

I claim:

1. The combination of a handle, a sleeve thereon flattened at one side and having a laterally facing shoulder at one end, opposite spaced pairs of lugs projecting from the flattened side of the sleeve at one end and near the other end, the last-named pair of lugs projecting to a higher plane than the other, a scythe blade extending laterally relatively to 25 and fitting flatly at its heel end upon the flattened side of the sleeve and abutting endwise against said shoulder and provided with a shank extending longitudinally and upon the flattened side of the said sleeve and fitting snugly between and against both lugs of each pair, the upper surface of the shank between the pair of lugs near said shoulder, lying in a higher plane than the latter, a bridge plate overlying said shank from the 30 pair of lugs adjacent said shoulder and engaging the shank of the blade, and means for causing said bridge plate to clamp the said shank firmly upon the plate.

2. The combination of a handle having a 40 flattened side at one end, a skeleton sleeve fitting snugly on the flattened end of the handle and comprising a plate fitting flatly against the flattened side of the handle, a pair of yokes projecting from the ends of said 45 plate and around the handle, a tie piece connecting the yokes at the opposite side of the handle from the flat portion of the sleeve, and pairs of spaced lugs projecting in the opposite direction from the sleeve from said yokes; 50 one of the latter having an extension providing a laterally facing shoulder; a scythe blade fitting at its heel end upon the flattened side of the sleeve and endwise against said shoulder and provided with a shank extending 55 from said heel end longitudinally and upon the flattened side of the sleeve and between and engaging the lugs of both pairs, clamping means securing the sleeve and shank flatly together near the free end of the 60 latter, a clamping plate fitting upon the shank and bridging the space between and spaced from the pair of lugs adjacent the heel end of the blade, bolts extending through the flattened portion of the sleeve 65 and said last-named lugs and said bridging

plate, and clamping devices adjustable on said bolts and engaging said bridging plate to cause the latter to clamp the adjacent portion of the shank firmly against the flattened portion of the sleeve.

3. In a scythe blade holding device, a sleeve comprising a flat plate provided at one end with a depending U-shaped yoke and at the other end with a similar but wider yoke, and a longitudinal tie-piece paralleling the plate and connecting the central portions of the yokes and provided with an opening, one end of the wide yoke having a shoulder overlying the plate and facing laterally thereof, and said plate having at its opposite end from said shoulder, a pair of upwardly-projecting spaced lugs and between said lugs and said shoulder, a second pair of upwardly-projecting spaced lugs, the plate also having a plurality of openings in the line of the spaces between the lugs and another opening vertically aligned with the opening in the tie-piece.

In testimony whereof I affix my signature.

JOHN M. WILKINSON.
